UNITED STATES PATENT OFFICE.

THOMAS H. STAGG, OF COLUMBUS, OHIO, ASSIGNOR TO THE KILBOURNE AND JACOBS MANUFACTURING COMPANY, OF COLUMBUS, OHIO, A CORPORATION OF OHIO.

DUMP-CAR.

No. 899,573.

Specification of Letters Patent.

Patented Sept. 29, 1908.

Application filed February 3, 1908. Serial No. 413,976.

To all whom it may concern:

Be it known that I, THOMAS H. STAGG, a citizen of the United States, residing at Columbus, in the county of Franklin and State 5 of Ohio, have invented certain new and useful Improvements in Dump-Cars, of which the following is a specification.

My invention relates to improvements in dump cars and comprises a swinging door or 10 apron which is automatically swung into position to form a side extension of the floor of the car box when the latter is in its dumped position, and when the car box is in its normal position the swinging extension automatically resumes its place beneath the car 15 where it is out of the way until the car is dumped again; it has especial application to cars used for railroad work, inasmuch as it deposits the lading beyond the track or rails 20 a sufficient distance to prevent the material from interfering with the movement of cars. When the car box is dumped, the lower side 25 swings inwardly and if the material is permitted to slide immediately from the bottom 30 of the car to the ground, it will tend to heap up and by gravity to fall or roll inwardly over the rail, and it is the object of my invention to prevent this. Although I have shown my swinging floor extension applied 35 to a side dump car, yet I may apply the same to an end dump car in which the car box is pivoted to dump towards its ends instead of its sides. To give my invention its highest efficiency I construct it to operate automatically, so that the lifting of the side door will cause the extension to be brought into its operating position.

In the drawings which are hereto attached and hereby made a part of this specification, 40 Figure 1 is an end view of the car having my improvements; Fig. 2 is an end view of a car having my improvements in its dumped position, one side of the car alone being completely illustrated; Fig. 3 is a side view of a 45 portion of a car having my improvements thereon.

Referring to the drawings in which the same numeral indicates the same part throughout, 1 is the truck of the car, 2 the 50 center sill, 3 the bracket mounted upon the center sill upon which the car box 4 is pivotally mounted at 5 to swing laterally; at the end of the car box is a laterally extending arm 6 pivoted at 7 to the outer end of which 55 at 8 is pivoted the side door 9 by means of

the hinge 10, the door being free to swing upon the pivot pin 8.

Pivoted to the arm 6 at 11 is a vertical arm 12 which in its lower portion is inserted through the box 13; on the arm 12 at an appropriate point are mounted the lugs 14, which when the car is dumped (see Fig. 2) engage the upper portion of the box 13 and prevent the further downward travel of the arm 12, whereby the arm 11 remains practically in the position it occupies at the moment the lugs 14 engage the upper edges of the box 13, whereas the car box 4 moves on downwardly, whereby the door 9 is opened and the lading permitted to slide outwardly 70 from the car.

Pivoted preferably to the underside of the outer edge of the car box at 15 is an extension or apron 16, which extends along the side of the car preferably from end to end thereof, 75 and is constructed to swing inwardly and outwardly; secured to this swinging apron or extension at 17 is a chain or flexible member 18 which at its other end is secured to the door 9 at 19; by means of the chain connection between the door 9 and the swinging extension or apron 16 the position of the said extension is controlled by the position of the side door, so that when the car is in its dumped position, the swinging extension or 80 apron on the dumped side is by means of the chain connection with the side door brought into the proper position to form a continuation of the bottom of the car box, whereby the lading is deposited at a point more remote from the car itself. 90

The dumped position of the car box is shown in Fig. 2, and referring thereto it is seen that the chain member 18 is taut, being made so by the rigid positioning of the door 9, and the further downward movement of the car box whereby the pivot 15 of the swinging extension 16 is carried lower down, and the outer end of the swinging extension having the chain 17 secured thereto, will 100 consequently be pulled upwardly and outwardly. In this manner the parts are properly adjusted when the car is dumped, to deposit the material at a desired distance away from the rails. It is evident that the distance to which the lading will be carried in being dumped will be determined by the width of the swinging apron 16, and also by the position it is made to assume with respect to the floor of the car box; if it is brought 110

into the plane of the floor, it will exercise the greatest effect possible in delivering the lading at a distance from the car, but in case it is desired to deliver it at a shorter distance, 5 the chain 18 may be of such length as to permit the swinging apron 16 to assume a position below the plane of the floor of the car box. It is not believed that in any case it would be desired to lift the swinging apron 10 16 above the plane of the car box floor. In this manner the same swinging apron may be used to meet various conditions.

It is not deemed necessary to show the position of parts on the upper side of a car 15 in dumped position, for the reason that the door remains closed and it is apparent that the swinging apron 16 would lie in a vertical plane at an angle with the plane of the car door, the chain being slack. Consequently 20 the swinging apron is in use on only one side at a time, and the construction thereof on either side of the car is identical with that on the other.

It may be mentioned that the gusset plate 25 20 is rigidly positioned on the arm 6 to hold the door 9 when opened in such position that it will with certainty return to its proper locking position when the car is righted.

What I claim is:

30 1. In a dump car, a member secured thereon to swing freely, a door adapted to be opened when the car is dumped, a flexible

connection between said door and said swinging member whereby when said car is dumped said member is drawn into a position practically in the plane of the floor of said car for the purpose of deflecting the material dumped to a point remote from the car. 35

2. In a dump car, a member pivoted to the lower side of the same adjacent to the outer edge thereof, a door adapted to be opened and held in elevated position when said car is dumped, and a flexible connection between said member and said door, whereby, when the car is in its dumped position, 40 said swinging member is brought practically into the plane of the car floor to deflect the dumped material outwardly away from the car. 45

3. In a dump car, a car box, a door thereon adapted to be held aloft in open position as the car box is dumped, a member hinged along the edge of the bottom of said car box to move therewith, a flexible member secured to said door and to said hinged member whereby the latter is raised to form an extension of the bottom of said car box during the dumping operation. 50

In testimony whereof I affix my signature in the presence of two witnesses.

THOMAS H. STAGG.
